UNITED STATES PATENT OFFICE.

LOUIS V. ARONSON, OF NEWARK, NEW JERSEY.

SPARKING PISTOL.

1,410,639.

Specification of Letters Patent. Patented Mar. 28, 1922.

Application filed December 19, 1921. Serial No. 523,412.

To all whom it may concern:

Be it known that I, LOUIS V. ARONSON, a citizen of the United States, residing at Newark, in the county of Essex and State 5 of New Jersey, have invented certain new and useful Improvements in Sparking Pistols, of which the following is a specification.

The invention relates to toys, and has as an object the provision of a toy simulating 0 an automatic pistol which, upon each discharge, will produce sparks, which sparks escape from the muzzle of the pistol and illuminate windows at the sides thereof, and which will not produce friction on the pyrophoric metal used to produce the sparks 5 while the sparking device is being set for operation.

An illustrative embodiment of the invention is shown in the accompanying drawings, in which—

Fig. 1 is a side elevation;

Fig. 2 is a vertical longitudinal section, with parts shown in elevation;

Fig. 3 is a horizontal transverse section 5 on line 3—3, of Fig. 2;

Fig. 4 is a vertical transverse section on line 4—4 of Fig. 2;

Fig. 5 is a detail section on line 5—5 of Fig. 2 upon an enlarged scale, and Fig. 6 is a like section showing a modification.

The casing 5 of the toy is preferably formed in two halves held together by means of up-standing lugs 6 on one of the halves, each lug provided with a recess 7, and the other half being provided with a tongue 8 adapted to be doubled about the lug 6 in the recess 7.

The working parts of the device are carried upon a plate 9 which may be secured to one half of the casing by tongues 10 which may extend through the casing and be clinched on the outside.

To produce friction upon a piece of pyrophoric metal a wheel 11, having a roughened surface 12, and a series of ratchet teeth 13 is shown as rotatably mounted upon the forward end of the plate 9. To hold a piece of pyrophoric metal a strap 12' is provided integral with the plate 9, the end of the strap being bent into the form of a cylinder 13', which cylinder may be truly cylindrical, or circular in cross section, or it may be triangular, as shown at 13'', Fig. 6, square, or any other desired form in cross section, the only requirement being that it

be a hollow body adopted to contain a piece of pyrophoric metal 14 of the same shape. Preferably the end of the strap which forms the cylinder is stopped short of the main body of the strap to produce a slot in the 60 cylinder for action of a pressure element.

A pressure element to provide pressure upon the pyrophoric element in the cylinder is provided in the form of a member 15 pivoted at 16 upon the plate 9, and having 65 a portion extending to the exterior of the casing and serrated at 17, whereby the element may be retracted by the thumb of the user. To provide pressure of the extension 18 upon the pyrophoric element a spring 70 19 has an end anchored on the strap 12' which is coiled about the pivot 16 of the member 15, and has its other end overlying a projection 20 carried by the member 15. As the element 14 is worn away the 75 extension 18 will follow downward into the slot in the cylinder 13', feeding the element 14 downward, and providing the requisite pressure thereon. The element may be renewed by merely revolving the element 80 15 about its pivot and placing a new element 14 in the cylinder which may be done from the exterior of the device. To provide movement of the friction element 11 a plate 21 is mounted to slide upon the plate 9, being 85 guided in an opening formed in an angularly extending portion 22 of the plate 9 at its end, and behind a portion 23 doubled over from the middle of the plate 9, the sliding plate carrying a series of pawl teeth 90 24. It is desired to have the member 11 remain stationary in one direction of the travel of the plate 21, so as to avoid unnecessary wear upon the pyrophoric element. The pawl teeth 24 are therefore adapted to 95 yield downwardly as the plate is moved forward, against the upward pressure of a spring 25 which has a fulcrum upon a projection 26 struck out at right angles from the plate 9, and provided with a recess to 100 retain the spring and which spring is also coiled about the pivot 27 of the trigger 28.

To hold the trigger in the normal position shown in Fig. 2 the spring 25 is seated in the grooved posterior of the trigger 28. The 105 trigger is preferably formed from a single piece of metal by doubling a portion on itself so as to provide an anterior portion at 29 and the grooved posterior portion already referred to.

The reciprocating plate 21 may be pressed rearwardly by means of a coil spring 30, anchored to the member 22 and to a lug 31 struck up from the reciprocating plate.

5 To enable the trigger 28 to act upon the plate 21 its upper end 32 lies behind a projection 33 from the plate 21, which projection has a rearwardly slipping cam surface upon its forward face. As the lower portion of the trigger is forced to the rear the plate 21 will be forced forward against the pressure of the spring 30 until the end 32 of the trigger slips off from the projection 33 below the same when the plate 21 will be 10 forcibly and suddenly returned to normal. The cam teeth 24 which yielded downwardly so as not to revolve the element 11 during their forward movement being pressed upward by spring 25 will catch in the teeth 13 15 of this element and cause sudden revolution as the plate 21 snaps to normal position, thus producing sparks from the pyrophoric element. The sparks will be projected from the open muzzle 34, and will illuminate a 20 transparent or translucent element 35 through windows between the strips 36 adjacent the muzzle of the toy. Preferably the material 35 will be colored, red being a 25 desirable color. The spaces between the 30 windows are so slight that each series of windows give the effect of a single opening when illuminated and such illumination has the effect of a long streak of flame similar to that seen when a firearm is discharged.

35 To suddenly check the rearward motion of the plate 21 and produce a sound somewhat similar to an explosion a member 37 is shown struck out from the plate 9, and a member 38 from the plate 21 adapted to seat against the member 37.

40 The toy may be operated as frequently as desired without recharging except at long intervals, when the pyrophoric element is worn out, and at each discharge a shower of 45 sparks is projected from the muzzle, and the colored windows are brilliantly illuminated, which action is accompanied by the snapping sound to simulate the sound of a pistol.

50 Minor changes may be made in the physical embodiment of the invention without departing from its spirit.

I claim—

55 1. A toy pistol comprising a casing having a relatively long barrel-forming portion and a series of openings in its sides, a covering of translucent material for each series

of openings, and sparking means within the casing to illuminate said openings.

2. A toy pistol comprising a casing having a relatively long barrel-portion having 60 a series of closely adjacent openings in the sides of the barrel adjacent to its muzzle, whereby each series is adapted to give the appearance of a single opening when illuminated, a covering of translucent material 65 for some of said openings, and means within the casing for producing sparks.

3. A toy pistol comprising a casing, a plate mounted within the casing, a sparking element holding loop of polygonal cross section 70 carried by said plate, a friction device mounted on the plate, means carried by the plate to press a sparking element held in said loop against the device, and means mounted on the plate to cause movement of 75 said device.

4. A toy pistol comprising a casing, a plate mounted within the casing, a strap struck from the plate, a sparking element holding loop carried by the strap, a friction 80 wheel mounted on the plate and carrying ratchet teeth, a slidable member mounted for reciprocation on the plate, pawl teeth on the member, means for yieldingly pressing said pawl teeth against said ratchet 85 teeth, and means for causing slow, forward and quick return movement of said member.

5. A toy pistol comprising a casing, a plate mounted in the casing, a friction wheel mounted on the plate, a member movably 90 mounted on the plate adapted to revolve said wheel during a portion of its movement, means mounted on the plate to cause slow outward and quick return movement of 95 said member, and means mounted on the plate to hold a pyrophoric element in contact with said wheel.

6. A toy pistol comprising a casing, a plate mounted in the casing, a friction wheel mounted on the plate, a member movably 10 mounted on the plate adapted to revolve said wheel during a portion of its movement, means mounted on the plate to cause slow outward and quick return movement of said member, means mounted on the plate to hold 10 a pyrophoric element in contact with said wheel, said last named means comprising a loop of polygonal cross section, and means mounted on the plate to press an element carried by said loop toward the wheel.

LOUIS V. ARONSON.
